UNITED STATES PATENT OFFICE.

JOHN F. SANDELL, OF CHICAGO, ILLINOIS.

INTERNAL-COMBUSTION ENGINE.

1,130,934.

Specification of Letters Patent.

Patented Mar. 9, 1915.

Application filed March 25, 1914. Serial No. 827,110.

To all whom it may concern:

Be it known that I, JOHN F. SANDELL, a citizen of the United States, residing at Chicago, in the county of Cook and State of Illinois, have invented a new and useful Improvement in Internal-Combustion Engines, of which the following is a specification.

My invention relates to an improvement 10 in the type of internal-combustion engine, which is adapted to use the heavier liquid hydrocarbons (fuel-oil) with compressed air as the fuel.

To start an engine of the kind referred to 15 with a torch, or the like, as heretofore, for heating the cylinder sufficiently in the first instance, takes an unduly long time; and one of the objects of my invention is to enable this starting to be effected in very much 20 less time.

Another object is to improve the engine in matters of detail, hereinafter described.

In the accompanying drawings, Figure 1 is a broken view in sectional elevation of an 25 oil-engine provided with my improvements, and Fig. 2 shows the head-portion of one cylinder by an enlarged sectional view.

A cylinder 3 rises on a suitable frame 4, and contains in its lower end a stuffing-box 5, through which works a piston-rod 6 connected as usual with a crank-shaft (not shown) and carrying a piston 7. In one side of the cylinder-wall is an air-inlet port 8, above which is the exhaust 9; and in the 35 opposite side of the wall is an air-inlet port 10, nearer the lower end of the cylinder than the port 8 and equipped with a spring-closed check-valve 11. A passage 12 in the cylinder-wall crosses the port 10 and extends 40 therein from below the lower end of the piston-stroke to a port 13 leading into the cylinder, normally closed by a door 14, and which may be used when desired, upon removing the door, to admit water when desired 45 for promoting combustion.

The engine, as thus far described, presents no features of novelty.

The cylinder-head 15 contains a flanged supplemental circular head 16 bolted in place through its flanges, whereby it is rendered readily removable for access to parts for repairing. This supplemental head clamps against offsets in the head of the cylinder, as shown in Fig. 1, a numerously-55 perforated sheet-metal plate or disk 17, of concavo-convex shape, which bears at its

center outwardly against a central rib 17^a on the inner face of the supplemental head, which is dished to form a chamber behind the disk. A firing-plug 18 extends through 60 the supplemental head and comprises, as its preferred construction, an externally-threaded tubular shell 19 of metal, in which seats at a collar 21 a porcelain tube 20 confined by a threaded sleeve 22 screwing into the shell against the collar; a metal rod 23 in the tube 20 having an electrical resistance-wire 24 fastened to its inner end and wound about the inner reduced section of the porcelain tube, the end of the wire being brazed 65 to a metal ring 25 wedged, for good contact, between tapering sections of the tube 20 and sleeve 19; and a sheet-steel cap 27 lined with mica 26 enveloping the wire 24. The tube 23 has a wire-connection *u* with one terminal 70 of a storage-battery, indicated at B in Fig. 1, the other terminal thereof being connected by a wire *w* with, or grounded on, the supplemental head 16. The capped section of the plug projects through the disk 17 into 75 the head-end of the cylinder.

The oil is fed into the cylinder through a nozzle 28 of the preferred construction illustrated in Fig. 2. It comprises a headed metal plug extending horizontally through 85 the cylinder-head and into the outer head-end of which a pipe 29 leads from a suitable source of fuel-oil supply (not shown). Ducts 30 extend lengthwise through the stem-portion of the plug and convergingly 90 toward a valve-seat in its inner end, in which seats a tapering valve 31 on a stem 31^a working centrally through the plug and having confined about its outer-end portion a spring 32 for holding the valve yieldingly 95 against its seat. The inner end of the plug has screwed upon it a metal cap 33 projecting into the cylinder and containing in its end a discharge-opening 34 inclining upwardly toward the inner face of the perforated disk 17, to cause oil discharging through it to strike the plate to one side of its center and be deflected against the cap 27. At 35, in Fig. 1, is shown a ring formed on the inner end of the piston for the air-deflecting purpose hereinafter explained.

In engines of the present type, the up-stroke of the piston, after passing the port 8, draws air through the latter into the cylinder after having drawn into the same sufficient air through the valved port 10, to avoid more than a sufficient vacuum behind

the piston to open the valve 11. In its downstroke, the piston compresses this air into the passage 12 until the piston, having opened the exhaust 9 for the escape of the 5 spent gases, opens the port 13 to admit the compressed air ahead of it into the cylinder, the ring 35 deflecting it from passing directly to the exhaust, from which only enough escapes to scavenge the cylinder.

10 The further advance of the piston compresses the air ahead of it, and oil is admitted to mix with it from the nozzle 28. While the engine is running, the heat generated in each cylinder by the compression 15 of the air by the piston therein vaporizes the oil and is supposed to be sufficient to explode the fuel-mixture for effecting the back-stroke of the piston.

15 The heat of compression and that from 20 the repeated explosions keep the plate 17^a in a red-hot condition; and by numerously perforating this plate the hot gases are admitted through the perforations into the chamber behind it to envelop the plate and 25 thus enhance its heated condition.

For starting the engine in the first instance, current from the battery B is turned on to heat the resistance-wire 24 and from it the metal cap 27, until the latter becomes 30 red-hot, for which a very few seconds (about 10 to 12) are required; when the battery is switched off. By cranking the engine to produce the air-compression in the cylinder and at the proper time forcing oil in the 35 usual way through the nozzle 28, the opening 34 directs the oil-discharge at an angle against the disk 17, whereby the concussion further divides it into small particles and deflects them in a fine spray against 40 the hot cap 27 to produce the explosion. After the first explosion the heat due to the air-compression in each cylinder supplemented by that of the disk therein, maintained in a red-hot condition as described, 45 and against which the oil is caused to strike by the inclined nozzle-exit 34, suffices to run the engine.

What I claim as new and desire to secure by Letters Patent is:—

50 1. In an internal-combustion engine, of the character described, the combination of

an electric circuit, a cylinder having air-inlet and exhaust ports, a piston in the cylinder, a nozzle for introducing liquid hydrocarbon into the cylinder near its head-end 55 and provided with an inclined discharge-opening in its inner end, a numerously-perforated concavo-convex metal plate confined about its edge in said head to form a chamber behind it and toward which said opening inclines, and a metal-capped electrical resistance-coil in said circuit, protruding through the cylinder-head and plate into the cylinder and into the path of liquid hydrocarbon discharging from said opening. 65

2. In an internal-combustion engine of the character described, the combination of a cylinder having air-inlet and exhaust ports, a piston in the cylinder, a supplemental head secured in the cylinder-head, a 70 concavo-convex numerously-perforated metal plate confined in the cylinder-head by said supplemental head to present its concave face to the direction of the piston-stroke, and forming with the supplemental head a 75 chamber, and a nozzle extending through the cylinder-head into the cylinder for introducing therein liquid hydrocarbon, said nozzle having a discharge-opening in its inner end inclining toward said plate. 80

3. In an internal-combustion engine of the character described, the combination of an electric circuit, a cylinder having air-inlet and exhaust ports, a piston in the cylinder, a supplemental head secured in the cylinder-head, a 85 concavo-convex numerously-perforated metal plate confined in the cylinder-head by said supplemental head and forming with the latter a chamber, a plug extending into the cylinder through the supplemental head and carrying on its inner end a metal-capped electrical-resistance coil included in said circuit, and a nozzle extending through the cylinder-head into the cylinder for introducing therein liquid hydrocarbon, said nozzle having a discharge-opening in its inner end inclining toward said plate. 90
